BRUSH MAKING MACHINE

Lloyd E. Jones, Pasadena, Calif.

Application August 11, 1942, Serial No. 454,423

11 Claims. (Cl. 300—3)

This invention relates to a brush making machine of that type in which two brush backs are simultaneously and identically moved respectively beneath a drill and a bristle inserter whereby the hole pattern is drilled in one block while the other, previously identically drilled, is simultaneously furnished with bristle tufts.

One of the objects of the invention is to provide a brush-making machine of the type described, in which the brush backs can be respectively drilled and filled complete from one end to the other without removing the brush blocks from the brush tables and reversing their position.

Another object of the invention is to provide a brush-making machine including a reciprocable cradle for moving the brush blocks longitudinally, tilttable about a fixed axis in different phases of its longitudinal movement to present the brush blocks at the desired longitudinal angles to the axes of the drill and bristle inserter, interconnected brush tables carried by said cradle transversely oscillatable about fixed axes to present the brush blocks respectively at the desired transverse angles to the drill and inserter, the axis of the cradle intersecting the axes of the brush tables in a common horizontal plane embracing said axes, whereby in any position of the brush blocks, the pressure exerted by the drill or by the inserter occurs at a neutral point, that is to say, at the points of intersection of said axes, eliminating any tendency for the brush blocks to shift during the drilling and filling operations.

A further object of the invention is to provide a brush-making machine of the character described, in which the points on the working faces of the respective brush blocks being acted upon by the drill or inserting means, are always in the plane of the axes of the supporting means so that the cam commonly employed for compensating differences in distance from the working face of the brush blocks to the datum positions of the drill and inserter, by raising or lowering the cradle assembly, is eliminated.

Other objects of the invention are to provide a much simpler, more flexible, less expensive construction for cradle assemblies; to provide greater drilling and filling speeds through quicker movement of the cradle assembly made possible by the lighter balanced cradle; and other objects of the invention will appear as the following description of a preferred and practical embodiment thereof proceeds.

In the drawings which accompany and form a

part of the following specification, and throughout the several figures of which the same characters of reference have been employed to designate identical parts:

5 Figure 1 is a side elevation of a brush-making machine embodying the principles of the subject invention;

Figure 2 is an end elevation of the same;

Figure 3 is a vertical section through the cradle assembly;

Figure 4 is a cross-section taken along the line 4—4 of Figure 3;

Figure 5 is a cross-section taken along the line 5—5 of Figure 4;

15 Figure 6 is a section taken along the line 6—6 of Figure 2;

Figures 7, 8, 9 and 10 are diagrammatic views showing successive positions of the cam track and cradle assembly in the making of a brush of the type shown in Figure 11;

Figure 11 is a side elevation of a brush, in which the bristle tufts converge at the center, flare at the ends, and are parallel in between;

25 Figure 12 is a side sectional view through a modified form of brush-making machine adapted to make the brush diagrammatically shown in Figure 14;

Figure 13 is an end view of the machine shown in Figure 12, part being broken away;

30 Figure 14 is a side elevation of a brush, in which the angular relation of the bristle tufts continually change from end to end of the brush;

Figure 15 is a side elevation, somewhat diagrammatic, of a modified form of cam track adapted to make the brush shown in Figure 16;

35 Figure 16 is a side elevation of a brush in which the bristle tufts converge at the center, flare at the ends, and continually change their angular relationship between the center and ends.

40 Referring now in detail to the several figures, and first advertizing to that form of the invention illustrated in Figures 1 to 10, inclusive, the brush-making machine is constituted by a supporting frame 1, comprising spaced side members 2 and 3, including the vertical standards 4

45 and 5 and the intermediate cross frame members 6 and 7. A shaft 8 is journaled in the upper ends of the standards 4 and 5, carrying a pulley 9, which forms the main drive for the machine, deriving its power preferably from an electric motor, not shown. The shaft 8 carries the cams 10 and 11, which operate respectively 50 the drill 12 and the bristle inserter 13, the lat-

ter mechanisms being carried by a cross bar 14 supported between the standards 4 and 5.

The bristle inserter mechanism 13 reciprocates, while the drill 12 rotates, as well as reciprocates. Rotary movement is imparted to the drill by a pulley 15 on the drill chuck 16, which pulley is driven by an electric motor, not shown. The drill is fed downward into the brush back by the cam 10, and when the hole has been drilled to the limit of its depth, the drill is withdrawn through the pull of the spring 17.

Said brush blocks are carried by brush tables 20 and 21, which in turn are mounted in a cradle 22. The cradle 22, as shown, has the shape of a rectangular frame, the opposite side members of which have the outwardly extending supporting flanges 23 and 24. The sides of said flanges are provided with the longitudinal rack bars 25 and 26 having teeth on their lower edge which mesh with pinions 27 and 28 carried at the inner ends of stub shafts 29 and 30 journaled in the respective standards 4 and 5 and extending outwardly beyond said standards. The outwardly extending ends of the said stub shafts are provided with gears 31 and 32 which mesh with vertically reciprocable rack bars 33 and 34.

The movement of the rack bars 33 and 34 imparts rotation to the pinions 27 and 28 and moves the cradle 22 forward or backward in a longitudinal direction.

In order to take the weight of the cradle and the imposed load produced by the pressure of the drill and bristle inserter off of the intermeshing rack bars and pinions 25, 27, 26 and 28, the flanges 23 and 24 are provided with longitudinal wear pieces 35 and 36, which rest upon rollers 37 and 38 carried by the stub shafts.

In making a brush of the type shown in Figure 11, it will be noted that the cradle 22 must first be tilted until the direction of the end bristles *a* is perpendicular to the axis of the drill and that this tilt must be progressively lessened up to the point *b*, where the bristles are perpendicular to the plane of the brush block. Then the cradle must move along in a plane perpendicular to the axis of the drill up to the point *c*. Then the brush block must tilt progressively in the opposite direction up to the point *d* in the center of the brush, and at that point it must suddenly tilt in the opposite direction, and this tilt must progressively diminish up to the point *e* where the bristles again become perpendicular to the plane of the brush block. The cradle must then travel in a plane perpendicular to the axis of the drill up to the point *f* where the bristles begin again to flare toward the opposite end of the brush and from this point the cradle must progressively increase the tilt up to the point *g* representing the flare at the opposite end of the brush.

The cradle 22 is guided in the execution of these tilting movements by means of rollers 39 and 40 journaled at opposite ends of the cradle and which ride upon a suitably shaped cam track having fixed and reversing oscillatable portions.

This cam track is best shown in the views comprehended in Figures 7 to 10, inclusive, and includes, for the type of brush shown in Figure 11, the identical fixed upwardly sloping end portions 41 and 42, the intermediate identical fixed horizontal portions 43 and 44 and the identical sloping portions 45 and 46 formed on a reversely oscillating shifter 47 pivoted in vertical alignment with the axis of the stub shafts 29 and 30. This cam track is duplicated on opposite sides of the machine and whichever sloping end of the shifter

47 is uppermost forms a continuous roller path with the adjacent fixed horizontal portion.

Referring now to the series of Figures 7 to 10, the cradle 22 is shown in Figure 7 supported in an inclined position with the right hand portion resting upon the rollers 37 and 38 on the stub shafts 29 and 30, and the left end supported by the rollers 39, which rest upon the sloping cam track portions 41 near the lower ends of said portions. As the cradle 22 is moved to the right through the rotation of the pinions 27 and 28 against the rack bars 25 and 26, the rollers 39 ride upward upon the sloping portions 41 of the cam track, progressively bringing the cradle to a horizontal position, which position is reached when the rollers 39 begin to travel upon the horizontal portions 43 of the cam track. In the position shown in Figure 7, the right hand end of a brush block carried by said cradle is so angularly related to the axis of the drill as to produce the terminal flare *a* indicated in Figure 11. The cradle 22 continues in horizontal position so long as the rollers 39 travel upon the horizontal portions 43 of the cam track. At this time the opposite rollers 40 rest without weight upon the right hand side of the shifter, since the predominant weight of the cradle is to the left of the common axis of the stub shafts 29 and 30. When the rollers 39 leave the horizontal portions 43 of the cam track and travel up the sloping portions 45 of the shifter 47 the cradle 22 will be reversely tilted, the rollers 40 simultaneously traveling down the sloping portions 46. This places the brush block in position for the drill to produce the flare shown at the right of the reference character *d* in Figure 11. The shifter 47 is latched in either of its inclined positions, shown in Figures 7 to 10, by means which will presently be described and automatically released when the cradle 22 reaches its neutral position upon the shifter shown in Figure 8. This permits the shifter immediately to tilt in the opposite direction to the position shown in Figure 9, the cradle 22 now being so angularly disposed that the drill produces the flare at the left of the reference character *d* in Figure 11. The shifter 47 is automatically latched in the reverse position shown in Figure 9. The righthand end of the cradle 22 then descends the sloping portions 46 of the shifter, progressively reducing the tilt of the cradle until the rollers 40 rest upon the fixed horizontal portions 44 of the cam track. By this time the predominant weight of the cradle is to the right of the common axis of the stub shafts 29 and 30 so that the left end of the cradle rests without weight upon the opposite side of the shifter. The cradle maintains a horizontal position while the rollers 40 travel over the fixed horizontal portions 44 of the cam track, during which time the axis of the drill is perpendicular to the brush block for drilling the holes in that portion of the brush between the reference characters *e* and *f* in Figure 11. When the rollers 40 move off of the horizontal portions 44 of the cam track onto the sloping portions 42, the cradle 22 begins to tilt at the opposite direction, the tilt increasing as the rollers 44 descend the slope for producing the flare at the terminal portion of the brush designated by the reference character *g* in Figure 11.

Now, referring to the means for latching and releasing the shifter, this is best shown in Figure 1, in which a manually oscillatable lever 48 is pivoted at an intermediate point in its length to the shaft 49, which extends between the side members 2 and 3 of the frame and carries on its

opposite side an arm 50 extending diametrically on both sides of the shaft 49 and in the same transverse plane as said lever. The lever 48 has a handle 51 at one end, by means of which it may be oscillated with respect to a detent quadrant 52, and having a detent 53 interengaging with notches in said quadrant to latch the lever end in the position illustrated in full lines in Figure 1, or in the reverse position when the detent 53 is in the upper notch 54 of the quadrant 52.

A pair of spiral springs 55 and 56 are provided for each shifter, fixed to the opposite ends of said shifters, one pair being anchored to the lever 48 and the other to the arm 50 at opposite sides of the axis of rotation of said rod and lever. Thus, when the lever 48 is in the full line position shown in Figure 1, the springs 55 on the left-hand side are stretched, while the springs 56 on the right-hand side are released. When the lever 48 is moved to a position in which the detent 53 is in the notch 54, conditions are reversed. The springs 55 are then relaxed and the springs 56 stretched. The shifter 47 is provided adjacent its opposite ends with the stops 57 and 58 adapted to engage notches in the pawls 59 and 60 which are pivotally mounted upon the cross-frame member 6. Said pawls are biased against said stops by the leaf springs 61 and 62, likewise secured to the cross frame member 6. The stop, pawl and leaf spring mechanism is duplicated on the opposite side of the machine, the opposite pawls and leaf springs being supported by the cross frame member 7. The cradle 22 carries adjacent opposite ends of its outwardly extending flanges 23 and 24, the pivoted trip members 63 which have free unidirectional movement being stopped from movement in the reverse direction by the abutment screws 88. The pawls 59 are in the path of movement of the respective trip members 63 as the cradle 22 moves to the right, or vice versa. Figure 1 shows the shifter 47 elevated at its left end and latched in this position, the notch in the pawl 59 engaging the stop 57. Before the cradle 22 moves toward the right, the operator of the machine sets the lever 48 in the full line position shown, stretching the springs 55 and releasing the springs 56. When the cradle 22 has moved forward to the point at which the rollers 39 ascend the sloping portions 45 of the shifters 47, the trip members 63 engage the pins 134 projecting inwardly from the pawls 59, pushing them away from the stops 57, permitting the stretched springs 55 to snap the shifters 47 into their opposite position against the lesser tension of the springs 56. In the meantime, the trip members 63 at the opposite end of the cradle 22 have tilted through contact with corresponding inwardly projecting pins, the opposite pawls 60, freely overriding said pins so as to be on the right-hand side thereof. When the left end of the shifters 47 were snapped down by the springs 56 upon release of the pawls 59 from the stops 57, the opposite ends of said shifters were moved upward until the notches in the pawls 60 snapped over the stops 58 under the urge of the leaf springs 62, latching the shifters in their reverse position. This brings the cradle to the position shown in Figure 9, and the cradle moves on to the right until it has assumed the position shown in Figure 10. At any time after the latching of the pawls 60 and before the cradle moves back in the opposite direction, the operator shifts the lever 48 from the full line position shown to the reverse

position, in which the detent 53 is in the notch 54, releasing the springs 55 and stretching the springs 56. In the reverse movement of the cradle 22, as soon as it reaches the position with the rollers 40 riding upon the slopes 46 of the shifters 47, the right-hand trip members 63 will engage the inwardly projecting pins on the pawls 60, releasing them from the stops 58 and causing the then stretched springs 56 to snap the shifters to their opposite position in which they are automatically latched.

Referring now particularly to Figures 2, 3 and 4, the brush tables 20 and 21 are mounted in spaced relation within the cradle 22, supported upon rollers 73 and 74 carried by the inwardly projecting pins 75 and 76 which are made fast to the end walls 77 and 78 of the cradle 22. It is to be noted that the axes 64 and 65, of the two sets of pins 75 and 76 lie in the same plane as the common axis of the stub shafts 29 and 30, about which the cradle 22 tilts, and perpendicular to said common axis. Each of the brush tables comprises a brush block support 66 extending between the end members 67 and 68. Said end members have the outwardly extending flanges 69 and 70, the under faces of which are shod with the wear pieces 71 and 72 resting upon the respective rollers 73 and 74. The brush block support 66 is parallel to the axis 64 of the roller pins and sufficiently depressed below the axis 64 so that when the brush block 18 is clamped to said support, the clamp means not being shown, the face of said brush block shall be in a common plane with said axis.

The end members 67 and 68 of said brush tables are interconnected both above and below the brush block support by the pivotal links 79 and 80, so that said brush tables oscillate in unison. The lower links 80 are connected by links 86 to fixed lugs 87 on the cradle, permitting the lower ends of the brush block tables to rise and fall following an arcuate path determined by movement of links 86 so as to compensate for differences in the distance from the axis center of the rollers 73 and 74 to the middle of the respective flanges 69 and 70 and the distances between said axis centers and the ends of said flanges. Thus the points of pivotal connection between the links 86 and the lower ends of the brush block tables become floating axes about which the tables tilt transversely. One of said brush block tables, for instance, the brush block table 21, has lug 81 secured at either end thereof, preferably connected by a wear piece 82 which is in the path of transverse reciprocation of an arm 83 moved by means which will presently be described. The arm 83 oscillates the brush block tables counterclockwise, as viewed in Figure 3, said brush block tables being oscillated in the opposite direction by means of a spring 84 stretched between one lug 81 and an anchoring pin 85 fixed to the cradle 22. It will be understood that since the brush block tables move linearly in contact with the rollers 73 and 74, throughout their range of oscillation, the point on the brush block intersected by the axis of the drill is always in the common plane which embraces the common axis of the stub shafts 29 and 30 and the axes 64 and 65 of the brush block tables. Consequently, no compensating cam is needed for moving the brush blocks closer or farther from the drill or the bristle inserting mechanism.

For varying the sidewise flare of the bristles, the end members 67 and 68 and the lugs 87 ex-

tend downward in parallel relation, each being provided with a series of holes 133 in any of which the pivots of the links 80 and 86 may be selectively engaged, the lower the link connections the greater the radius of swing and the smaller will be the angularity of the side flare of the bristle tufts.

Before advertiring to the mechanisms which produce the longitudinal reciprocatory movements of the cradle 22 and the oscillatory movements of the brush block tables carried by said table, it may be stated that the brush is completed during the travel of the cradle in one direction, to the right as shown in the drawings; that this movement is executed step by step, one step for each transverse row of bristle tufts, and that between each step of longitudinal movement of the cradle 22 the brush block tables perform a plurality of step by step transverse movements equal to the number of bristle tufts in a transverse row.

These step by step movements are produced and controlled by a series of cams on a shaft 89 which extends between the side frame members 2 and 3, being journaled in said members, and extending therebeyond on one side, as clearly shown in Figure 2. On this shaft is a ratchet wheel 90 having peripheral teeth 91 equal in number to the number of holes in the brush block pattern. Motion is imparted to said ratchet wheel and to the shaft 89 to which it is affixed by means of a crank 92 on the main power shaft 8, which transmits motion through a pitman 93 to a bellcrank lever 94 journaled in the side frame member 3, and which carries a pawl 95 operating upon the teeth 91 of the ratchet wheel. In that phase position of the shaft 8 in which the drill and the inserter are withdrawn from the brush block, the pawl 95 advances against the tooth 91 which it contacts, and moves the ratchet wheel one step; that is to say, in terms of the brush block, it moves said brush block through a distance equal to the spacing between two holes.

A cam 96 is fixed to the shaft 89 having an undulating surface providing a series of peaks 97 alternating with a series of valleys 98. This cam moves with the ratchet wheel 90. The cam 96 imparts step by step reciprocatory movement to an upwardly extending rack bar 99 through the intermediary of a roller 100 which is carried within the bifurcated lower end of said rack bar, and the distance on the surface of said cam between the top of a peak and the bottom of the adjacent valley represents a plurality of steps in the movement of said cam equal to the number of bristle tufts in a transverse row.

The rack bar 99 meshes with a gear 101 on a stub shaft 102, the latter being journaled in a housing 103 fixed to the standard 5. This stub shaft 102 carries a pinion 104 which meshes with the teeth of a transverse movable rack bar 105, (see Figures 2 and 6). Said transverse rack bar carries the arm 83 previously referred to, which bears against the lug 81 carried by the interconnected brush block tables 20 and 21.

For each step of movement of the ratchet wheel 90 and shaft 89, the arm 83 moves a step in a rightward direction, as viewed in Figure 2, while the roller 100 is descending from a peak to a valley on the cam 96, and while the roller is ascending from said valley to the adjacent peak, the arm 83 moves step by step to the left

for each step of movement of the ratchet wheel 90.

Another cam 106 is fixed to the shaft 89, moving step by step in synchronism with the ratchet wheel 90. This cam has a stepped spiral surface comprising a series of circular arcs 107 about the axis of the shaft 89 as a radius. The high and low points of the spiral are connected by a surface 112 which drops abruptly toward the middle of the cam, forming a shoulder. The cam 106 operates directly upon the rack bar 33 through the intermediary of a roller 108 journaled in the bifurcated foot of said rack bar. A lay shaft 109 is journaled between the standards 5 and 4 carrying at one end a pinion 110 directly engaged by the rack bar 34, and having at its opposite end a pinion 111 which meshes with the rack bar 33 and causes both the rack bars 33 and 34 to move simultaneously and in the same phase. It has already been pointed out that the rack bars 33 and 34 actuate the pinions 31 and 32 which operate the gears 27 and 28 that move the cradle 22 in a longitudinal direction.

The arcs 107 on the surface of the cam 106 are of sufficient linear extent to hold the rack bars 34 and 33 immovable while the rack bar 99 is traveling step by step from a peak of the cam 96 to a valley of the same cam. In other words, the cradle 22 stays in one longitudinal position while the brush block tables oscillate step by step in one direction to produce a transverse row of holes in one brush block and simultaneously to insert a corresponding transverse row of bristle tufts in the other brush block. At the end of the transverse oscillation of the brush block tables, the cam 106 has moved so that the roller 108 of the rack bar 33 drops to the level of the next adjacent arc. This produces a reciprocation of the rack bars 33 and 34 which moves the cradle 22 one step longitudinally to the right. Then the brush block tables oscillate step by step in the opposite direction to produce another transverse row of holes and tufts respectively in the two brush blocks, after which the cradle 22 makes another step to the right, and so on until the entire brush block pattern has been completed. This occurs when the cradle 22 has moved to the right through the full extent of its range of travel.

At this time the roller 108 falls from the shoulder 112, causing the rack bars 33 and 34 to descend, quickly moving the cradle 22 in a leftward direction through its entire range of travel to its starting position, the shifter 47 being reversed before the cradle passes its middle position on its return.

The brush-making machine as above described may be adjusted to make the type of brush shown in Figure 16 by substituting a cam track such as that shown in Figure 15, which is characterized by the absence of horizontal portions corresponding to the portions 43 and 44 shown in Figure 7.

In this form of cam track the shifter 115 is so designed that the movable sloping portions 113 and 114 of the shifter align with the fixed sloping portions 116 and 117 and have the same angle of slope when so aligned. The length of the sloping portions 113 and 114 must be sufficient to enable the rollers 39 or 40, as the case may be, to ride high enough to tilt the cradle 22 in a reverse direction at a small angle bringing the sloping portions of the shifter into alignment with the corresponding sloping portions of the fixed cam

track, to provide the continuously changing angular pattern between the points *h* and *i* of the brush in Figure 16, with reverse flares at said points.

The shifter then reverses, the cradle continuing toward the right, the roller 40 riding down the common slope of the contiguous movable and fixed portions 114 and 117 of the cam track, providing the bristle tuft pattern from *i* to *j* in Figure 16.

Now, advertizing to that form of the invention shown in Figures 12 and 13, this shows a cam track adapted to make a brush of the type shown in Figure 14, in which the angularity of the bristle tufts continually changes from one end of the brush to the other, and in addition it shows means for adjusting the fixed sloping portions at the opposite ends of the cam track so that the angle of flare at the opposite ends of the brush can be altered at will. In this form of the invention the cradle 22 is shown shiftable transversely with respect to the fixed axis of the stub shafts 29 and 30, the axis 29 only, being shown. The end portions of the cam track are represented by the guide members 118 and 119 pivoted to the cross frame at the points 120 and 121, and adjustably fixed at any angle by the clamp means 122, Figure 13, secured to said guide members, and which may be clamped at any point along the fixed quadrants 123 and 124. The guide members 118 and 119 are provided with the track flanges 125 and 126 projecting inwardly, and the overhanging keeper flanges 127 and 128, which form between them channels 129 and 130 for the rollers 131 and 132 carried by the cradle 22 adjacent its opposite ends. The cradle moves from left to right, being first at its maximum angle of slope, which angle diminishes until the cradle is in a mid-position between the guide members, in which position it is horizontal and then it reverses its angularity, progressively increasing its slope until it reaches its limit of travel in a rightward direction. Inasmuch as there is no sudden change in angularity of the bristle tufts in the middle of the brush, no reversible shifter is required. It is understood that Figures 12 and 13 only illustrate enough of the machine to disclose the type of cam track employed, and that other details of structure are the same as in that form of the invention illustrated in Figure 1, excepting as regards those elements which are concerned with the operation and control of the shifter and which are obviously omitted.

While I have in the above description disclosed what I believe to be a preferred and practical embodiment of the invention, it will be understood to those skilled in the art that the details of construction and the arrangement of parts as shown and described are by way of example, and not to be construed as limiting the scope of the invention as defined in the appended claims.

What I claim is:

1. In a machine for making brushes with flared bristle tufts, a reciprocable drill for making bristle tuft holes in the face of a brush block, said drill having a fixed axis, means forming a fixed axis perpendicular to the axis of said drill and intersecting the axis of said drill, a tiltable cradle supported by said axis forming means, means for moving said cradle step by step across said axis forming means to bring different linear zones of said brush block into registry with the axis of the drill, a brush block table supported in said cradle on an axis fixed with respect to said cradle, passing through the axis of said drill, in-

tersecting said first mentioned supporting axis at a point which shifts longitudinally of said brush block table supporting axis but necessarily remains in the axis of the drill, said brush block table being constructed to support a brush block with an element of its face to be drilled coincident with the supporting axis of said brush block table, means for oscillating said brush block table step by step to bring different points in each linear zone of the brush block into the axis of the drill, and means to shift the brush block table relative to its supporting axis in a plane perpendicular thereto to bring each drilling point on the face of said brush block to the point of intersection of the cradle supporting axis and the axis of the drill.

2. In a machine for making brushes with flared bristle tufts, a reciprocable drill for making bristle tuft holes in the face of a brush block, said drill having a fixed axis, means forming a fixed axis perpendicular to the axis of said drill and intersecting the axis of said drill, a cradle supported by said axis forming means, means for moving said cradle step by step across said axis forming means to bring different linear zones of said brush block into registry with the axis of said drill, a cam track engaged by said cradle, shaped to impart desired tilting movements to said cradle while moving across said axis forming means, a brush block table supported in said cradle on an axis fixed with respect to said cradle, perpendicular to the supporting axis of said cradle, passing through the axis of said drill, and intersecting said cradle supporting axis at a point which shifts longitudinally of said brush block table supporting axis but necessarily remains in the produced axis of the drill, said brush block table being constructed and arranged to support a brush block with an element of its face to be drilled coincident with the supporting axis of said brush block table, means for oscillating said brush block table step by step to bring different points in each linear zone of the brush block into the axis of the drill, and means to shift the brush block table relative to its supporting axis in a plane perpendicular thereto to bring each drilling point on the face of the brush block to the point of intersection of the cradle supporting axis and the axis of the drill.

3. In a machine for making brushes with flared bristle tufts, reciprocable tools movable along fixed spaced parallel axes, the one for drilling a hole pattern in a brush block, the other for simultaneously filling a similarly drilled brush block, means forming a fixed axis perpendicular to the axes of said tools and intersecting the axes of said tools, a tiltable cradle supported by said axis forming means, means for moving said cradle step by step across said axis forming means to bring different linear zones of said respective brush blocks into registry with the axes of said tools, brush block tables supported in said cradle on spaced parallel axes fixed with respect to said cradle, perpendicular to the supporting axis of said cradle, respectively passing through the axes of said tools, and intersecting said cradle supporting axis at points which shift longitudinally of said brush block tables but necessarily remain in the axes of said tools, said brush block tables being constructed and arranged to support the respective brush blocks with an element of the face of each to be drilled or filled, coincident with the supporting axes of the respective brush block tables, means for oscillating said brush block tables in unison, step by step to bring different

points in each linear zone of the respective brush blocks into the axes of the respective tools, and means to shift said brush block tables relative to their supporting axes in planes perpendicular thereto, to bring each drilling point on the face of the respective brush blocks to the respective points of intersection of the cradle supporting axes and the axes of said tools.

4. In a machine for making brushes with flared bristle tufts, a reciprocable drill for making bristle tuft holes in the face of a brush block, a cradle for carrying a brush block, means rotatable about a fixed axis perpendicular to the axis of said drill and intersecting the axis of said drill, engaging cooperating means on said cradle for moving the latter across the axis of said rotatable means, cam controlled means for operating said cradle moving means to impart step by step movement to said cradle across the axis of said rotatable means to bring different linear zones of said brush block into registry with the axis of said drill, a cam track engaged by said cradle shaped to impart desired tilting movements to said cradle while the latter is moving across said axis, a brush block table supported in said cradle on an axis fixed with respect to said cradle, perpendicular to the supporting axis of said cradle, passing through the axis of said drill, and intersecting said cradle supporting axis at a point which shifts longitudinally of said brush block table supporting axis but necessarily remains in the axis of the drill, said brush block table being constructed and arranged to support a brush block with an element of its face to be drilled coincident with the supporting axis of said brush block table, means for oscillating said brush block table step by step to bring different points in each linear zone of the brush block into the axis of the drill, and means to shift the brush block table relative to its supporting axis in a plane perpendicular thereto to bring each drilling point on the face of the brush block to the point of intersection of the cradle supporting axis and the axis of the drill.

5. In a machine for making brushes with flared bristle tufts, a reciprocable drill for making bristle tuft holes in the face of a brush block, a cradle for carrying a brush block, means rotatable about a fixed axis perpendicular to the axis of said drill and intersecting the axis of said drill, engaging cooperating means on said cradle for moving the latter across the axis of said rotatable means, cam controlled means for operating said cradle moving means to impart step by step movement to said cradle across the axis of said rotatable means to bring different linear zones of said brush block into registry with the axis of said drill, a cam track engaged by said cradle having sloping extreme portions for giving opposite tilt to the cradle and brush block to produce the opposite flares of the holes in the opposite end portions of the brush block, said cam track having a middle portion pivotally shiftable about the axis of said rotatable means to reversely inclined positions for providing abrupt reversal in the flare of the holes at an intermediate region of the brush block, means for reversing the middle portion of said cam track, a brush block table supported in said cradle on an axis fixed with respect to said cradle, perpendicular to the supporting axis of said cradle, passing through the axis of said drill, and intersecting said cradle supporting axis at a point which shifts longitudinally of said brush block table supporting axis but necessarily remains in the axis of the drill, said brush block table being constructed and arranged to support a brush

block with an element of its face to be drilled coincident with the supporting axis of said brush block table, means for oscillating said brush block table step by step to bring different points in each

5 linear zone of the brush block into the axis of the
drill, and means to shift the brush block table
relative to its supporting axis in a plane perpen-
dicular thereto to bring each drilling point on the
face of the brush block to the point of intersec-
10 tion of the cradle supporting axis and the axis of
the drill.

3. You can obtain a form to claim a homestead with flased

6. In a machine for making brushes with flared bristle tufts, a reciprocable drill for making bristle tuft holes in the face of a brush block, a cradle for carrying a brush block, means rotatable about a fixed axis perpendicular to the axis of said drill and intersecting the axis of said drill, engaging cooperating means on said cradle for moving the latter across the axis of said rotatable means, cam controlled means for operating said cradle moving means to impart

20 said rotatable means, cam controlled means for operating said cradle moving means to impart step by step movement to said cradle across the axis of said rotatable means to bring different linear zones of said brush block into registry

25 with the axis of said drill, a cam track engaged by said cradle having sloping extreme portions for giving opposite tilt to the cradle and brush block to produce the opposite flares of the holes in the opposite end portions of the brush block.

30 said cam track having a middle portion pivotally
shiftable about the axis of said rotatable means
to reversely inclined positions for providing abrupt
reversal in the flare of the holes at an interme-
diate region of the brush block, means for re-

35 dante region of the brush block, means for reversing the middle portion of said cam track, latch means for holding the middle portion of said cam track in either of its inclined positions against the bias of said reversing means, said latch means being tripped by said cradle at the

40 latch means being tripped by said cradle at the determined point for reversing the inclination of said cradle, a brush block table supported in said cradle on an axis fixed with respect to said cradle, perpendicular to the supporting axis of said cradle, passing through the axis of said drill.

45 said cradle, passing through the axis of said drill, and intersecting said cradle supporting axis at a point which shifts longitudinally of said brush block table axis but necessarily remains in the axis of the drill, said brush block table being

50 constructed and arranged to support a brush block with an element of its face to be drilled coincident with the axis of said brush block table, means for oscillating said brush block table step by step to bring different points in each linear

55 zone of the brush block into the axis of the drill, and means to shift the brush block table relative to its supporting axis in a plane perpendicular thereto to bring each drilling point on the face of the brush block to the point of intersection of the cradle supporting axis and the axis of the
60 drill.

00 arm.

7. In a machine for making brushes with flared bristle tufts, a reciprocable drill for making bristle tuft holes in the face of a brush block, a cradle for carrying a brush block, means rotatable about a fixed axis perpendicular to the axis of said drill

and intersecting the axis of said drill, engaging cooperating means on said cradle for moving the latter across the axis of said rotatable means, cam controlled means for operating said cradle 70 moving means to impart step by step movement

70 moving means to impart step by step movement to bring different linear zones of said brush block into registry with the axis of said drill, a cam track engaged by said cradle having sloping extreme portions for giving opposite flares to the
75 holes in the opposite end portions of the brush

block, said cam track having a middle portion pivotally shiftable about the axis of said rotatable means to reversely inclined positions for providing abrupt reversal in the flare of the holes at an intermediate region of the brush block, means for reversing the middle portion of said cam track, spaced rollers mounted in said cradle on a common axis fixed with respect to said cradle, perpendicular to the supporting axis of said cradle, passing through the axis of said drill and intersecting said supporting axis at a point which shifts longitudinally of said roller axis between said rollers, but necessarily remains in the axis of the drill, a brush block table tiltably supported by said rollers to move across said roller axis, said brush block table being constructed and arranged to support a brush block with an element of its face to be drilled coincident with said roller axis, means for moving said brush block table step by step across said roller axis, to bring different points in each linear zone of the brush block into the axis of the drill, and means to shift the brush block table relative to its roller supporting axis in a plane perpendicular thereto to bring each drilling point on the face of the brush block to the point of intersection of the cradle supporting axis and the axis of the drill.

8. In a machine for making brushes with flared bristle tufts, a reciprocable drill for making bristle tuft holes in the face of a brush block, a cradle for carrying a brush block, means rotatable about a fixed axis perpendicular to the axis of said drill and intersecting the axis of said drill engaging cooperating means on said cradle for moving the latter across the axis of said rotatable means, a cam operatively connected with said cradle moving means to impart step by step movement to said cradle to bring different linear zones of said brush block into registry with the axis of said drill, a cam track engaged by said cradle having sloping extreme portions for giving opposite flares to the holes in the opposite end portions of the brush block, said cam track having a middle portion pivotally shiftable about the axis of said rotatable means to reversely inclined positions for providing abrupt reversal in the flare of the holes at an intermediate region of the brush block, means for reversing the middle portion of said cam track, spaced rollers mounted in said cradle on a common axis fixed with respect to said cradle, perpendicular to the supporting axis of said cradle, passing through the axis of said drill and intersecting said supporting axis at a point which shifts longitudinally of said roller axis between said rollers, but necessarily remains in the axis of the drill, a tilttable brush block table supported by said rollers to move across said roller axis, said brush block table being constructed and arranged to support a brush block with an element of its face to be drilled coincident with said roller axis, a cam operatively connected to said brush block table for moving said brush block table step by step across said roller axis to bring different points in each linear zone of the brush block into the axis of said drill, said cams being mounted on a common drive shaft in such relative phase that the step by step

movement of said brush block table occurs at the intervals between the steps of movement of said cradle, and means to shift said brush block table relative to said roller axis, in a plane perpendicular thereto, to bring each drilling point on the face of the brush block to the point of intersection of the cradle supporting axis and the axis of the drill.

9. In a machine for making brushes with flared bristle tufts, a reciprocable drill for making bristle tuft holes in the face of a brush block, a cradle for carrying a brush block, means rotatable about a fixed axis perpendicular to the axis of said drill and intersecting the axis of said drill, engaging cooperating means on said cradle for moving the latter across and oscillatably about the axis of said rotatable means, cam tracks at opposite sides of said cradle moving means pivotally mounted at their inner ends and arcuately adjustable to vary the angularity of the endwise flare of the bristle tufts, cam track engaging means on said cradle adjacent opposite ends thereof, alternately engageable with the adjacent cam tracks, to be guided thereby as the middle of the cradle passes the axis of said cradle moving means, and a brush block table carried by said cradle for supporting a brush block in operative relation to said drill.

10. In a brush making machine, a reciprocable drill having a fixed axis for making bristle tuft holes in a face of a brush block, means for supporting said brush block to permit rectilinear movement and tilting in a longitudinal direction having an axis intersecting the axis of said drill and being perpendicular thereto, means for supporting said brush block to permit rectilinear movement and tilting in a transverse direction having an axis intersecting the axis of said drill and the axis of said first mentioned supporting means, the axes of both said supporting means lying in a common plane whereby the three said axes intersect at a common point, and means to bring predetermined points on the face of the brush block successively into coincidence with the common point of intersection of the three said axes.

11. In a brush making machine, a reciprocable drill having a fixed axis for making bristle tuft holes in a face of a brush block, means for supporting said brush block to permit rectilinear movement and tilting in a longitudinal direction having an axis intersecting the axis of said drill and being perpendicular thereto, means to advance the brush block longitudinally step by step, means for supporting said brush block to permit rectilinear movement and tilting in a transverse direction having an axis intersecting the axis of said drill and the axis of said first mentioned supporting means, the axes of both said supporting means lying in a common plane whereby the three said axes will intersect at a common point, means to oscillate the brush block transversely step by step intermediate the steps of longitudinal movement, whereby predetermined points on the face of the brush block will be brought into successive coincidence with the common point of intersection of the three said axes.

LLOYD E. JONES.
